UNITED STATES PATENT OFFICE.

CHARLES B. BURGER, OF PITTSBURGH, PENNSYLVANIA, ASSIGNOR TO GULF OIL BURNER COMPANY, OF PITTSBURGH, PENNSYLVANIA, A CORPORATION OF PENNSYLVANIA.

LIQUID-FUEL BURNER.

Application filed July 13, 1926. Serial No. 122,187.

This invention relates to liquid fuel burners; and it comprises a burner having an upper compartment with means for feeding liquid fuel thereto and having openings adjacent the peripheral edge of the burner, and a lower compartment having openings corresponding to the openings of the upper compartment, together with means permitting free circulation of air through one compartment to cause a suction in the other compartment; all as more fully hereinafter described and as claimed.

The present burner is particularly adapted for household use and, in detail, comprises a base member, an intermediate member of general conical formation which overlies the base member and which is spaced therefrom by means of a series of curved vanes depending from either the intermediate member or erected on the base member and a hood of domed formation, either with or without one or more plates in spaced relation to the intermediate member, enclosing the intermediate member and defining a space so that the assembled structure is divided into upper and lower compartments. Central openings are provided in the base and intermediate members to permit of an updraft of air through the grate bars of the furnace in which the burner is located, and communicating openings are provided in the periphery of the burner for causing an intimate mixture of air from the lower chamber with oil and air from the upper chamber. An upright feed pipe is provided for the introduction of oil into the upper chamber, this pipe terminating in a distributor cap, the peripheral face of which is formed with vertical grooves communicating with radial grooves formed in its upper face and diverging from the upper end of the oil feed pipe, whereby the oil flowing from the supply pipe will be evenly distributed over the intermediate member.

Among the objects of the present invention is the provision of a simple, easily assembled and inexpensive burner and improvements in the details thereof for causing efficient operation and for protecting the different parts. A specific object is the provision of an oil distributor which is constructed to effect a uniform distribution of the fuel oil through the provision of a plurality of small sized radial grooves formed in the distributor. Another

specific object is the provision of means for the protection of the distributor, consisting of one or more shields or hoods. A further object of the invention is to provide means for evenly distributing oil to the openings for the purpose of effecting uniform operation.

In the accompanying drawings:

Figure 1 is a side view of the present invention, partly in section;

Figure 2 is a sectional view taken along line 2—2 of Figure 1, part of the section being broken away to show the overlying fuel openings;

Figure 3 is a top plan view of the distributor showing the positioning of the radial grooves therein;

Figure 4 is a side view of the distributor;

Figure 5 is a top view of the plug which is screwthreaded into the distributor;

Figure 6 is a side view of the plug shown in Figure 5;

Figure 7 is side view, partly in section, of another form of my invention in assembled position within a furnace;

Figure 8 is a side view of a modified form of distributor;

Figure 9 is a top plan view of the burner shown in Figure 7, partly broken away;

Figure 10 is a vertical section, taken along the line 10—10 of Figure 9;

Figure 11 is a section, taken along the line 11—11 of Figure 10;

Figure 12 is a vertical section of a modified form of burner in which there is incorporated a different form of heat shield;

Figure 13 is a fragmentary sectional view of another modified form of burner in which the upper compartment is defined by a cap which rests upon the distributor, and in which means is provided for directing the current of air passing into the upper compartment;

Figure 14 is a detail view, partly in section, of a modified form of base support for the burner whereby it may be positioned within a furnace.

Referring to the drawings:

The circular base 1 of the burner comprising the present invention is open at both ends. This base member is adapted to rest on the grate 2 of any suitable type of furnace commonly used in houses. That portion of the grate not covered by the base member is packed with fire-brick 3. The base member

is preferably circular or of ring shape, and is formed along its upper edge with a continuous outwardly curved lip 4. An intermediate member 5, of general conical shape is superimposed upon the base member, but is spaced therefrom by a series of curved vanes 6 which are integrally formed therewith or with the base casting, the outturned portions of the vanes all being directed at a suitable angle to the periphery of the burner so that the projection of discharge of air between adjacent vanes makes an angle of less than 45° with a tangent to the periphery of the burner at the point of discharge. These vanes serve to give the air passing through the lower compartment 7 a swirling motion, thereby producing a more uniform flame and increasing the efficiency of the burner. The intermediate member 5 is provided with a central opening 8 and an annular flange 9 which is upturned and adapted to cooperate with the downwardly extending flange 10 of a domed hood 11. In the trough formed by the upturned flange 9 and the body portion of member 5 a series of small downwardly directed holes 22 is formed, such holes opening into the air passage in the lower chamber 7 defined by the vanes 6.

A vertical oil pipe 12 extends upwardly from beneath the grate of the furnace, through the lower compartment 7 and into the upper chamber 13, formed by member 5 and hood 11. Mounted upon the end of pipe 12 is a distributor 14 comprising a body portion and an annular downwardly extending flange 15, the said flange being interiorly screw-threaded as indicated at 16. Radial grooves 17 are formed in the face or upper surface of the distributor 14, originating from the opening for the pipe 12 and increasing in depth from this point to the outer edge of the distributor face. Vertical grooves 18 are formed in the peripheral edge of the distributor 14 and communicate with the radial grooves 17, decreasing in depth from the point of communication to the lower edge of flange 15.

A plug 19, shown in detail in Figure 6, which is inserted under the cap, is externally screwthreaded as at 20, the screw threads being adapted for cooperation with threads 16 of the distributor cap. Spaced lugs 21 are formed integrally with the lower face of plug 19, these lugs acting to space the distributor cap from the shoulder formed by opening 8 in member 5, thereby permitting a circulation of air up through the grate 2, opening 8, upper chamber 13, and out through the small openings 22.

An overflow pipe 23 extends into the trough formed by flange 24 of the base member 1, and is designed to carry off excess oil in case the flame of the burner is accidentally extinguished and the burner flooded.

In the form of invention shown in Figures 7 to 11, inclusive, of the drawing, the trough 25 of the base member is provided with guard

26, which may be integral or detachable for cleaning purposes, overlying the connection of the overflow pipe with trough 25. The overflow pipe preferably leads to an oil supply control means, such as for instance that shown in my copending application, Serial No. 739,368, filed September 23, 1924. The base member is mounted upon the grate bars of the furnace by nuts and bolts 26^a and ears 27, that part of the grate which is not occupied by the burner being sealed with firebrick or tile 29. Instead of forming the base 30 with ears 27 and fastening the burner in position by bolts 26^a, the base may be provided with a plurality of downwardly extending screw-threaded rods 66, as shown in Figure 14 which are tapped into the screwthreaded holes 67 of the base and preferably held in position by means of nuts and washers. Feet 68 are axially bored and threaded to receive the ends of rods 66, and are tapered at their lower ends to engage the support upon which the burner is positioned. Axially extending projections 69 are formed integrally with the body portions of the feet, as shown in the drawing. In order to operate efficiently the burner comprising the present invention should rest in a level position. The modified form of adjustable support shown in Figure 14 permits of accurate adjustment so that the burner may be positioned to give most efficient service in operation.

The base member 30 of the burner is in the form of an upwardly extending collar, the wall of which converges to form a circular opening and which terminates in an outwardly turned and downwardly inclined lip or flange 31 as in the form of invention hereinbefore described.

The intermediate member 32, of frustoconical shape, has integrally formed wings or vanes 33 depending from its under surface, the heel portions 34 of such vanes being of considerable length to extend within the constricted opening in the base member of the burner and to thereby support the intermediate member against shifting relative to the base. The upper face of the intermediate member is formed adjacent its peripheral edge with an undulatory upper surface, and a plurality of openings 35, each of which communicates with a depression in said undulatory surface, extend downwardly to overlie the openings between adjacent vanes 33 and communicate therewith.

As in the form of invention before described, the intermediate member 32 is formed with a central opening 36, the upper termination of such opening being bevelled as at 37 to provide a seat for the distributor 38. The distributor, in this instance, is formed as a unitary structure and it consists of a circular body advantageously of brass or the like, formed with a hub portion 39 having a vertically extending opening pass-

ing axially therethrough for the reception of the oil supply pipe. The upper face of the distributor is recessed as at 40, thereby providing a small basin for the collection of oil, 5 and the remainder of the upper face of the distributor is formed with a plurality of spaced radially extending grooves 41, each of which communicates with a corresponding vertical groove 42 formed in the peripheral face of the distributor. The grooves 41 increase in depth from the center of the distributor toward its edge and are of such proportion and small size that the adhesion of oil offers an appreciable resistance to the flow 10 of oil over the distributor. The large number of small grooves and the resistance which is offered by their small size serves to equalize the flow of oil around the periphery of the burner. A plurality of oil feeding holes 43 are formed in the hub portion 39 of the distributor and communicate, at an angle, with the axial bore thereof and with the basin 40 to distribute the oil evenly into such basin.

Depending from the under side of the distributor 38 and integral with it, are a plurality of downwardly projecting lugs 44, the outer edges of which are shaped to conform to the bevelled shoulder 37 and the bore 36 of the intermediate member, thus providing a 25 secure seat for the distributor. A section of the bore of the distributor is screwthreaded, and an oil feed pipe 45 is fastened in this portion.

Mounted upon and overlying the intermediate member is a hood 46 of heat-resisting metal provided at its periphery with a downwardly extending rim 47 and a horizontally disposed face 48 (Figure 10) adapted to rest upon the corresponding face of the intermediate member. The hood is provided with a knob 50 which is axially bored to receive a bolt 51. Concavo-convex plates 52 and 53 are mounted within the hood 46, and in a position to overlie the distributor, by means 40 of the bolt 51. Spacing collars 54 encircle the bolt 51 and are interposed between the hood and concavo-convex plates, and between adjacent plates to hold the assembled structure in spaced relation.

50 A modification of this construction is shown in Figure 12 wherein the dome 55 terminates at its periphery in a downturned flange 56 which, as distinguished from the constructions hereinbefore described, is spaced from the peripheral edge of the intermediate member 32. A concavo-convex plate 57 is formed with lugs 58 projecting from its convex face such lugs being axially bored and aligned with holes provided in the hood for the reception of bolts 59 which serve to hold plate 57 in position within the hood. Spacing collars 60 encircle the bolts 59 and space a second concavo-convex plate 61 within the hood and plate 57. The shanks of bolts 59 are screwthreaded and nuts 62 are

provided to hold the structure in assembled position. The concavo-convex plate 57 is provided at its periphery with a downwardly extending flange 63 which engages the periphery of the intermediate member and a flat surface 64 which constitutes the support for the hood structure upon the intermediate member. The flange 63 is spaced a slight distance from the downwardly extending flange 56 of the hood to define an annular opening through which air may pass to circulate between the spaced plates to cool the upper chamber of the burner. The plates 57 and 61 are both formed with holes 65 to provide for communication between the air spaces defined by the plates and hood.

55 The plates 52 and 53, shown in Figure 10, and the spaced plates shown in Figure 12 are preferably, although not necessarily, of concavo-convex shape to conform to the shape of the overlying hood of the burner. By providing the plates in spaced relation and by positioning them to overlie the distributor carbonization of the oil flowing therefrom is prevented. It is desirable to maintain the upper chamber of the burner relatively cool to prevent preignition of the fuel or its carbonization. In use, however, the flame around the periphery of the burner converges about the convex hood and thereby heats it 60 highly. The provision of spaced plates, such as have heretofore been described, eliminates undesirable heating of the upper chamber of the burner because of the fact that such plates, in themselves, serve as a means to block the heat radiating from the 65 hood.

70 A further modification of my invention is shown in Figure 13 wherein a cap 70, provided with openings or vents 71 and a handle 72, overlies the distributor, of the form hereinbefore described, and is spaced from it by an annular shoulder 73 extending inwardly from the interior surface of the cap or hood and resting upon the grooved upper face of the distributor. A flaring skirt 74 is formed as an integral part of the hood 70, but such skirt terminates short of the periphery of the burner.

75 In operation, oil is forced upwardly through the oil supply pipe and overflows upon the face of the distributor where it is conveyed by the grooves for even distribution over the conical upper surface of the intermediate member. Air flowing up through the central opening in the intermediate member and around the bottom of the distributor into the upper chamber assists the flow of oil down through the openings in the periphery of the upper chamber. A 80 strong current of air flows through the lower chamber and out between the base and intermediate members, being directed by the curved vanes. This rush of air causes a suction or lowering of pressure in the upper 85

chamber, expelling the oil therein through the openings at its periphery. In effect there is an ejector action.

5 Ignition of the mixture of oil and air takes place at the outlets of the openings around the burner, and the flame is given a spiral or whirling motion by reason of the positioning of the curved vanes.

10 Particular advantage is gained by grooving the face and side flanges of the distributor inasmuch as the oil tends to adhere to the metal side walls of the grooves, and the slower flow occasioned by such adhesion contributes to a more even and constant supply of fuel to the point of combustion. The minor portion of air serves to cool the shield and the distributor.

15 This application is a continuation in part of my copending application, Serial No. 20 691,720, filed February 9, 1924.

What I claim is:—

20 1. A liquid fuel burner comprising an upper compartment having openings formed therein adjacent the peripheral edge of the burner, a lower compartment having similar openings, the openings of the upper compartment overlying the openings of the lower compartment, and means for separately feeding liquid fuel and air to the upper compartment.

25 2. A liquid fuel burner comprising a base member open at its lower end, a hood overlying said base member, means for supplying oil within said hood, an intermediate plate between said base member and hood, said intermediate plate being formed with an aperture for admitting air between the hood and the plate, a member carried by said intermediate plate to distribute oil thereover and a series of vanes interposed between said base member and intermediate plate, and spacing said base member and intermediate plate apart.

30 3. A liquid fuel burner comprising a base member open at both ends, an intermediate conical member overlying said base member, a series of curved vanes for spacing said intermediate member from said base member, and a hood adapted to seat upon the peripheral edge of said intermediate member whereby said burner is divided into upper and lower compartments.

35 4. A burner for liquid fuel comprising a base, an intermediate member, and a hood, a fuel supply pipe extending upwardly through openings formed in the base and intermediate member, a distributor cap on the end of said fuel supply pipe, said cap being radially grooved communicating openings in the base and intermediate member of such relative size that the circulation of air through the base member causes a suction above the intermediate member.

40 5. An oil distributor for liquid fuel burners comprising a cap, an oil supply pipe received in a central opening formed in said

cap, radial grooves formed in the face of said cap, said grooves being of increasing depth from the central opening in said cap to the outer edge thereof, and peripheral grooves formed in said cap in communication with said radial grooves, said peripheral grooves being of decreasing depth from the point of communication with the said radial grooves.

45 6. The combination with a liquid fuel burner of a cap, a continuous downwardly extending flange formed on said cap, said flange being interiorly screwthreaded, an externally screwthreaded plug adapted to be received within the flange of said cap, downwardly extending lugs formed on the lower face of said plug for cooperation with the burner structure whereby said cap is supported by the burner structure but spaced from it.

50 7. A fuel burner comprising an upper compartment, means for delivering air and oil thereto, a lower compartment, and means for delivering air thereto, means between the compartments for causing a swirling action of the air as it leaves the lower compartment, and means for causing a delivery of the air and oil of the upper compartment and the swirling air from the lower compartment to a common combustion point.

55 8. A liquid fuel burner comprising a base, an intermediate member, and a hood assembled to provide upper and lower compartments, the said upper compartment having a plurality of openings therein overlying a series of openings in said lower compartment, said intermediate member being formed with an undulatory surface adjacent its periphery.

60 9. A liquid fuel burner comprising a base, an intermediate member, and a hood assembled to provide upper and lower compartments, the said upper compartment having a plurality of openings therein overlying a series of openings in said lower compartment, an aperture formed in said intermediate member for admitting air to the upper compartment, and means within said hood and in spaced relation therewith for preventing excessive heating of said upper compartment.

65 10. A liquid fuel burner comprising a base, an intermediate member, and a hood assembled to provide upper and lower compartments, the said upper compartment having a plurality of openings therein overlying a series of openings in said lower compartment, the said intermediate member being formed with an undulatory surface adjacent its periphery, and means within said hood and in spaced relation therewith for preventing excessive heating of said upper compartment.

70 11. A liquid fuel burner comprising a base, an intermediate member, and a hood assembled to provide upper and lower compartments, an oil distributor in the upper compartment, an oil feed pipe detachably secured thereto, means in said lower compartment for

- 10 12. A liquid fuel burner comprising a base, a hood overlying said base, and an intermediate member between said base and hood for defining upper and lower compartments in the burner, a distributor for fuel oil in said upper compartment, a series of spaced plates within said hood and overlying said distributor for preventing excessive heating of the upper compartment.
- 15 13. A liquid fuel burner comprising a base, a dome-shaped hood overlying said base, and an intermediate member between said base and hood for defining upper and lower compartments in the burner, a distributor for fuel oil in said upper compartment, a series of spaced concavo-convex plates affixed in spaced relation to the inner surface of said hood and overlying said distributor for preventing excessive heating of the upper compartment.
- 20 14. A liquid fuel burner comprising a base, an intermediate member overlying said base and spaced therefrom to define peripheral openings, said intermediate member being formed with a central opening, the said intermediate member being formed with openings adjacent its periphery; a distributor for liquid fuel supported above said intermediate member and in alignment with the opening
- 25 therein, and a hood supported to define a chamber above said distributor whereby fuel oil flowing therefrom is shielded from the heat of a flame around the periphery of the burner.
- 30 15. A liquid fuel burner comprising a base, a hood, an intermediate member formed with a centrally disposed opening, a fuel supply pipe extending through the opening, and a distributor mounted on the end of the pipe, said distributor comprising a substantially cylindrical cap formed with radially extending grooves in its circular end face increasing in depth from the center to the circumference thereof, and cooperating contiguous grooves formed in the peripheral cylindrical face communicating with the radially extending grooves and decreasing in depth from the upper extremity thereof.
- 35 16. A liquid fuel burner comprising an upper member, a lower member, and an intermediate member forming upper and lower spaced compartments, said upper compartment being formed with apertures disposed adjacent the outermost edge of said burner, said lower compartment being formed with openings disposed adjacent the outermost edge of said burner, said apertures and openings being of such size as to permit the free circulation of air therethrough, said apertures being disposed over said openings, and means permitting the free access of air to both compartments, whereby circulation of air through the openings in the lower compartment will induce a flow of air through the apertures in the upper compartment.
- 40 70 75 In testimony whereof, I have hereunto affixed my signature.

CHARLES B. BUERGER.
